ELECTRICAL TESTING APPARATUS FOR
HERMETICALLY SEALED REFRIGERA-
TOR PUMP UNITS

Thomas H. Bunker, Jackson Heights, N. Y.

Application March 18, 1949, Serial No. 82,032

2 Claims. (Cl. 175—183)

1

This invention relates to electrical testing apparatus, and one object thereof is the provision of a practical, useful and efficient yet simple testing unit for testing hermetically sealed refrigeration pump units.

The apparatus includes an ammeter which is used to determine the common, running and starting poles or binding posts of the electric pump unit, thereby eliminating wire color schemes and the possibility of wrong connections through confused colors and disconnected leads.

The above broad as well as additional and more specific objects will become apparent in the following description, wherein characters of reference refer to like-numbered parts in the accompanying drawings. It is to be noted that the drawings are intended solely for the purpose of illustration, and that it is therefore neither desired nor intended to limit the invention necessarily to any or all of the exact details shown except insofar as they may be deemed essential to the invention.

Referring briefly to the drawings, Fig. 1 is a perspective view of the self-contained testing unit.

Fig. 2 is a schematic wiring diagram of the testing unit and its application and hook-up in testing a refrigeration pump unit.

Referring in detail to the drawings, the numeral 10 indicates a cabinet, housing, box or other suitable container which may be made of wood or any other suitable or desired material. In the front wall or panel of the box 10, shown at 11, an ammeter 12 is visibly mounted. Also mounted in the panel 11 are a test lamp 13, a replaceable fuse 14, and switches 15, 16, 17, 18 and 19 whose functions are indicated by captions on the panel and which are shown schematically in Fig. 2. A plug-in line connector cord is shown at 20, leading from the box 10, and leads 21, 22, and 23 extending from the top of the box have on their ends battery clips 24 which, although not shown so, are preferably insulated. Captions on top of the box indicate the nature of each of these leads, and they are also shown in the wiring diagram.

In Fig. 2 the numeral 25 indicates schematically the refrigerator housing and the numeral 26 indicates or represents the split phase or capacitor-start motor which drives the pump, not shown, the starting winding of the motor being shown at 27 and the running winding at 28. The common terminal of the two motor windings is shown at 29, the other terminal of the starting winding at 30 and the other running terminal at 31.

2

As shown in the wiring diagram of Fig. 2, the "on" and "off" or line switch 18 is of the single throw double-pole type, and the lamp switch 15 is of the double throw double-pole type. A jumper 32 connects one terminal 33 of the switch 15 diagonally with the opposite pivot terminal 34 of the switch arm 35, and another jumper 36 connects the terminal 37 of the switch 15 with the terminal 38 of the switch 18. One line conductor 39 leads to the terminal 40 of the switch 18; the other line conductor 41 leads through the fuse 14 to a terminal 42. From the latter one lead 43 leads through the lamp 13 to the terminal 33, and another lead 44 leads to the terminal 45 of the switch 15, the terminal 46 of the latter being idle. From the other pivot terminal 47 of the switch 15 a lead 48 connects with the terminal 49 of the switch 18.

A lead 51 leads into the ammeter 12 from the terminal 50 of the switch 18, and the test lead 23 leads from the ammeter. A lead 52 connects the terminal 38 with a common point 53 from which one lead 54 extends to the pivot terminal 55 of the arm 56 of the switch 17, and another lead 57 leads to the terminal 58 of the switch 19. A capacitor 59 is, as shown, connected across the switch 16, and from one common terminal 60 thereof a lead 61 connects to the other pole 62 of the switch 19; from the other common terminal 63 thereof a lead 64 connects with the other pivot terminal 65 of the switch 17. The latter is converted to a reversing switch by means of the crossed jumpers 66 and 67 connected at one end to the poles 68 and 69, respectively, and at the other end to the poles 70 and 71, respectively. The test lead 21 extends from the pole 69, and the test lead 22 extends from the pole 68.

It is apparent that the reversing switch 17 reverses the direction of rotation of the split phase or capacitor start motor by interchanging the running and starting leads 21 and 22.

In use, with the reversing switch in "forward" position, shown in Fig. 2, with the line switch 18 closed and the switch 19 open, the leads 22 and 23 are applied to the three terminals 29, 30 and 31 of the pump motor 26 in the three possible combinations, and that one which gives the lowest ammeter reading indicates that the remaining terminal is the common terminal 29. That is, when the leads 22 and 23 are connected to the terminals 30 and 31 the lowest ammeter reading of the three combinations is obtained, which signifies that the terminal 29 is the common terminal of the motor 26. Then the lead 23 is attached to the common terminal 29, and the

leads 21 and 22 are attached to the two remaining poles 30 and 31.

If the motor 26 then starts when the starting switch 19 is closed momentarily, then the operation is repeated with the reversing switch 17 in reversed position, the ammeter reading being noted in both cases. That position of the switch 17 which gives the lower ammeter reading is then the one for correct rotation of the motor. In case the motor does not start in either position, a rhythmic back-and-forth movement of the switch 17 will often free the stuck pump-unit and initiate starting.

For ground or continuity tests for or through the motor windings or any part of the circuit, the switch 15 may be used as follows. It is to be noted that when this switch is thrown to the right, Fig. 2, the lamp 13 is in parallel with the test circuit and serves as a pilot light. When the switch is thrown to the left the lamp is in series with the line circuit, so that it will indicate whether any of the windings or circuits of the pump unit are continuous or open, with the leads 21, 22 and 23, of course properly applied to the terminals of the motor 26.

The starting capacitors, 59 may also, in an obvious manner, be tested for efficiency on the ammeter.

It is thus apparent that a very handy and practical test unit has been provided for the purposes set forth, which is simple and inexpensive in construction and operation and efficient in use.

Obviously, modifications in form or structure may be made without departing from the spirit or scope of the invention.

I claim:

1. An electrical testing apparatus for substantially the purposes described comprising a double-pole single throw line switch having one pair of terminals thereof adapted to be connected to a power line, an ammeter having one terminal thereof connected to one of the other pair of terminals of said line switch, the other terminal of the ammeter having a test lead extending therefrom, a double-pole double throw reversing switch including a forward pair of terminals and a reverse pair of terminals and a pivoted switch arm, one of the pivot terminals of said reversing switch having a lead joining the same to the other of said other pair of terminals of said line switch, 50 a single throw starting switch having one terminal thereof connected to said other of said other pair of terminals of said line switch, a lead connecting the other of said terminals of said

starting switch with the other of said pivot terminals of said reversing switch, a jumper connecting one of the forward terminals of the reversing switch with the diagonally opposite reverse terminal thereof, a jumper connecting the other forward terminal of the reversing switch with the other of said reverse terminals, a test lead extending from one of said forward terminals of said reversing switch, and a test lead extending from the other of said forward terminals of said reversing switch, said test leads being adapted to be connected severally to the common terminal and the starting and running terminals of a split phase motor in three obvious combinations, said ammeter indicating its lowest reading in that one of said combinations wherein said first mentioned test lead is connected to said common terminal.

2. The apparatus set forth in claim 1, one of the conductors of said power line having a lamp 20 in series therein, a second double-pole double throw switch, said conductor being broken adjacent said lamp thereby providing two juxtaposed ends, one of said juxtaposed ends having a lead connecting the same to one of the intermediate terminals of said second double-pole double throw switch, one terminal of one of the pair of end terminals of the latter switch having a jumper leading therefrom and joined to said conductor on the other side of said lamp, a lead connecting the other terminal of said one pair of end terminals of said latter switch with said other of said pair of terminals of said line switch, and a jumper connecting the other of said last-named juxtaposed ends to the other of said intermediate terminals of said second double-pole double throw switch.

THOMAS H. BUNKER.
